UNITED STATES PATENT OFFICE.

EVANGELINE K. ALLISON, OF MIAMI, ARIZONA.

COMBINATION EYEBROW PENCIL.

Application filed June 16, 1921. Serial No. 478,043.

To all whom it may concern:

Be it known that I, EVANGELINE K. ALLISON, citizen of the United States, residing at Miami, in the county of Gila and State 5 of Arizona, have invented certain new and useful Improvements in Combination Eye-brow Pencils, of which the following is a specification.

The invention has reference to eye-brow 10 pencils and has for its primary object to provide an article of this character having in combination therewith brush and comb means respectively projecting from opposite sides thereof.

An additional object is to provide an eye-brow pencil of novel design and construction and embodying a hollow barrel or pencil case in which the eye-brow grease stick is adjustably contained.

With the above and other objects in view the invention may be said to reside generally in the details of construction, combination and arrangement of parts as will be herein-after more fully pointed out and described, 25 reference being had to the accompanying drawings, wherein—

Figure 1 is a top plan of the device showing the arrangement of the brush and comb elements. Figure 2 is a longitudinal end 30 view of the pencil as seen from the brush side. Figure 3 is a horizontal, cross-sectional view through the barrel of the device, as taken on lines 3—3 of Figure 1. Figure 4 shows the case in which the article 35 is enclosed. Figure 5 is an end view of the case with the flap-end fastened.

The grease-stick for shading the eye-brows is contained within a hollow tube or case 1, which constitutes the barrel of the pencil, 40 which the grease-stick being indicated at 2. The barrel is preferably made square as indicated by the cross-section of Fig. 3 and is closed at opposite ends by knurled caps 3 and 4, the former closing the lower end of the barrel 45 and the latter, the top end. By removing both caps the grease-stick 2 can be forced longitudinally through the barrel so as to project an appreciative distance above the top end, when desired to be used. After 50 using, both caps may be screwed back in place on the barrel, thus protecting the stick

and keeping it clean of grit and other foreign substances.

The comb 5 and brush 6 are located adjacent the upper ends of the barrel and on 55 opposite sides as illustrated in the several views of the drawing. Both are arranged in alignment with the longitudinal axis of the barrel and provide additional eye-brow dressing units. The pencil may be 60 made of aluminum metal or other suitable material affording a durable and light structure adequate for the purpose in view.

The case for the pencil comprising an elongated pouch 7, for containing the device 65 and a mirror may be provided on the inside of closing flap 9 so that one can see to apply the eye-brow pencil. A loop 10 is carried by the flap and engages button 11 on the pouch for fastening the flap after the pencil, 70 has been inserted in the case. It may thus be seen that the invention provides an eye-brow pencil of the combination type adapted to be conveniently carried about the person and permitting the insertion of fresh grease-stick in the pencil as they are used up.

The foregoing description and accompanying drawings have reference to what might be considered to be the approved or preferred form of my invention. I desire it to be understood, however, that I may make such changes in the construction, combination and arrangement of parts, materials, dimensions, et cetera, as may prove expedient and fall within the scope of the appended claim.

Having thus described my invention, what I claim as new and desire to secure by Letters Patent is:—

A device of the character specified comprising a barrel having an eye-brow-smoothing brush projecting oppositely from one face thereof and a comb projecting from the opposite face, a grease-stick slidably contained within the barrel, and closing cap at opposite ends of the barrel and having screw threaded engagement therewith.

In testimony whereof I affix my signature in presence of a witness.

EVANGELINE K. ALLISON.
